LAND, TEXAS

RAIL-GAUGING DEVICE

Application filed March 26, 1928. Serial No. 264,672.

This invention relates to new and useful improvements in rail gauging devices.

One object of the invention is to provide a device for gauging the rail of a railroad track, which may be set and operated by one man.

A further object of the invention is to provide a rail gauging device which will be complete in itself and which one man may conveniently carry while inspecting the track.

A still further object of the invention is to provide a device for gauging rails, which may be easily and quickly placed in position and which may be left in place against the rail, if necessary, until permanent fastenings can be applied.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a view showing a device constructed in accordance with the invention applied to a rail and the tie supporting the same, portions being shown in elevation and portions in section,

Fig. 2 is a horizontal cross-sectional view taken on the line 2—2 of Fig. 1, and

Fig. 3 is a transverse sectional view taken on the line 3—3 of Fig. 2.

In the drawings the numeral 10 designates a chair having an upstanding transverse abutment 11 rising from the central portion of a base plate 12. The chair is preferably formed of one piece and may be made from a strip of metal suitably bent or forged into shape; however, it may be made in any suitable way. The abutment 11 is provided with an inclined seat 13 located between two upright bosses 14.

In order to fasten and quickly apply the chair, the plate 12 is provided with a plurality of depending prongs or pointed studs 15 which may be slightly curved. The chair may be placed upon the tie A and any con-

venient instrument used for driving the prongs 15 into said tie. The purpose of the prongs is to resist longitudinal displacement from the rail B and it is obvious that the prongs would not need to be very long and by slightly curving them away from the rail, they will resist a great strain.

The purpose of the chair is to support one end of a jack which comprises a barrel 16 having internal screw-threads 17 at one end for receiving a screw-threaded shank 18 having a head 19 at its outer end. A plug 20 is suitably fastened in the opposite end of the barrel and carries a swivel head 21 formed integral therewith. A cap 22 is confined on the head 21 so as to form a swivel connection and said cap is provided with an enlarged flat face 23.

The barrel is provided with opposite apertures 24 and a turning bar 25 is slidable through said apertures. Heads 26 at each end of the bar prevent its displacement from the barrel, although it may be freely slid through the barrel. The bar is used to rotate the barrel and thus retract or extend the shank 18. The jack may be used in placing the chair in position, the head 19 being employed as a hammer.

In using the device, the chair 10 is positioned as shown in the drawings and the head 19 is slid into the seat 13 between the bosses 14, the seat being just wide enough to freely receive the head, but to prevent rotation thereof. The head 19 rests against the abutment 11. Owing to the swivel connection of the cap 22, the face 23 may be placed flat against the web C of the rail B. This disposes the jack at an angle and throws the upper portion of the bar 25 away from the rail so that it may be freely swung to rotate the barrel. After the jack is in place the spikes D are pulled and then by rotating the barrel 16 the shank 18 is expelled, whereby the rail B is displaced inwardly of the track, as is shown in dotted lines in Fig. 1.

The workman adjusts the rail to the proper gauge and then redrives the spikes D to hold it in place. If he does not have means for driving spikes, he can leave the device in

place until the rail can be permanently secured. The entire equipment is small and may be easily handled and carried. One man can readily operate the device and can gauge 5 the rail to a minute degree.

Various changes in the size and shape of the different parts, as well as modifications and alterations, may be made within the scope of the appended claims.

10 What we claim is:

1. In a rail gauging device, a chair having an inclined abutment and adapted to removably engage with a tie, and a jack having a head at one end engaging the abutment of 15 the chair and a swiveled cap at the other end for engaging the web of a rail.

2. In a rail gauging device, a chair having an inclined abutment and adapted to removably engage with a tie, a jack including 20 a barrel having a swiveled cap at one end and a shank screw-threaded into the opposite end of the barrel, a head on the shank engaging the abutment of the chair, and means for turning the barrel to expel or retract the 25 shank.

3. The combination in a rail gauging device of a jack, and a rail chair having a base provided with an upright abutment having an inclined seat for receiving the head of the 30 jack, bosses on each side of the seat of the chair abutment, and prongs depending from the chair base.

4. In a rail gauging device, a chair having means for removably fastening it against 35 movement, and a jack engaging said chair and having a swiveled cap for engaging the web of a rail, whereby said chair and jack may be engaged with either side of a rail.

5. In a rail gauging device, a chair having 40 prongs for driving into a tie, whereby said chair is held against displacement, and a jack engaging said chair and having a swiveled cap for engaging the web of a rail, whereby said chair and jack may be engaged with either side of a rail.

In testimony whereof we affix our signatures.

LOUIS B. QUAM.

MARSHALL W. NORTHINGTON.

50 JOHN D. SAWYER.
